United States Patent Office

Des. 185,001
Patented Apr. 28, 1959

185,001

MICROFILM READER

Robert S. Houghton, Orlando, Fla.

Application November 15, 1957, Serial No. 48,486

Term of patent 14 years

(Cl. D61—1)

FIG. 1

FIG. 2

FIG. 3

FIG. 4

Fig. 1 is a front perspective view of a microfilm reader, showing my new design;

Fig. 2 is a front elevational view, to a reduced scale,
Fig. 3 is a side elevational view, to a reduced scale,
the opposite side being substantially a mirror image
thereof; and

Fig. 4 is a top plan view thereof.

I claim:

The ornamental design for a microfilm reader, as shown
and described.
